U.S. Cl. 161—165 4 Claims**ABSTRACT OF THE DISCLOSURE**

A vibration damped sandwich system comprising two hard plates and interposed between the plates a vibration damping interlayer comprising a graft polymer of methacrylic acid methyl ester or optionally methacrylic acid methyl ester together with a copolymerizable carboxylic acid, especially acrylic and/or methacrylic acid, on a copolymer of 30 to 40% by weight of vinyl acetate, 30-40% by weight of 2-ethylhexyl acrylate, 30 to 10% by weight of dibutyl maleate and 5 to 15% by weight of crotonic acid.

The present invention relates to vibration damped sandwich systems having interlayers made of graft polymers of methacrylic acid methyl ester or optionally methacrylic acid methyl ester together with a copolymerizable carboxylic acid, especially acrylic and/or methacrylic acid, on vinyl acetate/2-ethylhexyl acrylate/dibutyl maleate/crotonic acid copolymers.

It is known from South African Specification No. 5,269 that highly valuable vibration damping materials of a broad temperature band suitable for damping bending vibrations of metal sheet constructions can be prepared by copolymerizing monomers whose homopolymers differ in their second order transition temperature by at least 20° C. The above specification also reports that as vibration damping materials having a broad temperature band there can be used, among others, predominantly amorphous copolymers of esters of alcohols with 4 to 12 carbon atoms with acrylic and maleic acid and vinyl esters of fatty acids with 2 to 3 carbon atoms, for example vinyl acetate/2-ethylhexyl acrylate and/or dibutyl maleate copolymers.

It has now been found that graft polymers of methacrylic acid methyl ester or optionally methacrylic acid methyl ester together with small amounts of a copolymerizable carboxylic acid, especially acrylic and/or methacrylic acid, on copolymers of vinyl acetate, suitable esters of unsaturated polymerizable carboxylic acids and an unsaturated copolymerizable acid, preferably crotonic acid, have outstanding damping properties and a very broad temperature band width and are thus especially suitable for the vibration damping of sandwich systems of hard plates, in particular metal sheets. Suitable esters are especially those of acrylic acid and maleic acid with alcohol components having 3 to 12 carbon atoms, preferably 2-ethylhexyl acrylate and dibutyl maleate. With these polymers, the vibration damping effect of which critically depends on the weight proportion of the monomers, very broad damping curves can be obtained having very high maximum damping values. From the economical point of view they have the advantage of being rather cheap.

The graft polymers of methylmethacrylate or optionally methylmethacrylate together with a copolymerizable carboxylic acid (acrylic and/or methacrylic acid) on copolymers of 30 to 40% by weight of vinyl acetate, 30 to

40% by weight of 2-ethylhexyl acrylate, 30 to 10% by weight of dibutyl maleate and about 10% by weight of crotonic acid are prepared by free radical initiated polymerization at a temperature in the range of from about 60 to about 180° C. of a solution of the copolymer in monomeric methylmethacrylate or a mixture of methylmethacrylate and a copolymerizable carboxylic acid (acrylic and/or methacrylic acid), which solution contains the catalyst. Especially good results are obtained with graft polymers of 40 to 80% by weight of methylmethacrylate or a mixture of methylmethacrylate with a copolymerizable carboxylic acid (acrylic acid and/or methacrylic acid) on 60 to 20% by weight of the copolymers specified above, for example a graft polymer of 50% by weight of methylmethacrylate or of 50% by weight of a mixture of 90% by weight of methylmethacrylate and 10% by weight of acrylic acid and/or methacrylic acid on 50% by weight of the aforesaid copolymer. As initiator for the polymerization tertiary butylhydroperoxide may be used in the usual concentration.

The present invention provides sandwich systems of hard plates, in particular metal sheets, having vibration damping, self-adherent interlayers of graft polymers of methacrylic acid methyl ester or optionally methacrylic acid methyl ester together with a copolymerizable carboxylic acid, especially acrylic and/or methacrylic acid on vinyl acetate/2-ethylhexyl acrylate/dibutyl maleate/crotonic acid copolymers, for which interlayers there are used graft polymers of 40 to 80% by weight of methylmethacrylate or methylmethacrylate together with a copolymerizable carboxylic acid (acrylic and/or methacrylic acid) on 60 to 20% by weight of a copolymer consisting of 30 to 40% by weight of vinyl acetate, 30 to 40% by weight of 2-ethylhexyl acrylate, 30 to 10% by weight of dibutyl maleate and 5 to 10% by weight of crotonic acid.

FIGS. 1a to 1c of the accompanying drawings are plots against temperature of the loss factor d_{comb} to illustrate the superior efficiency of the novel systems. The curves in FIGS. 1a and 1b show the loss factor d_{comb} of two metal sheet arrangements of the invention as a function of temperature. For comparison, one of the most effective vibration damping materials known for metal sheet arrangements was used, namely a copolymer of 63% by weight of vinyl acetate and 37% by weight of dibutyl maleate containing as plasticizer 15% by weight of 2-ethylhexyl phthalate and 15% by weight of tricresyl phosphate, calculated on the mixture (curve FIG. 1c). The copolymer of curve 1c was a thermoplastic adhesive especially suitable for producing vibration damped metal sheet sandwich systems comprising two outer metal sheets and a self-adherent thermoplastic as damping interlayer. Systems of this type provide a damping effect which is extremely high in its maximum and cannot be exceeded for physical reasons (cf. H. Oberst and A. Schommer, Kunststoffe, volume 55, page 634 (1965), especially FIG. 9). In a symmetrical arrangement comprising two metal sheets, each having a thickness of 0.5 millimeter, and an interlayer 0.3 millimeter thick, the loss factor d_{comb} of the combined system, measured in the bending wave method (cf. for example H. Oberst, L. Bohn and F. Linhardt, Kunststoffe, volume 51, page 495 (1961)), almost reaches the value d_{comb} of 1. The known metal sheet damping by one-side damping coatings which are applied by spraying, trowelling or bonding in the form of layers of so-called vibration damping materials show loss factors generally of less than $d_{comb}=0.2$ with technically reasonable thickness or ratios of coating mass to plate mass of the combined system. With metal sheet sandwich systems which gain growing importance in recent times, it is possible to obtain damping values that are increased by a multiple, as shown by the present example, when the interlayer material has the appropriate composition and thickness.

The temperature band width of the damping of the metal sheet sandwich system does not only depend on the viscoelastic properties of the interlayer and the steel sheets but also to a considerable extent on the "geometry" of the arrangement, i.e. on the ratio of the layer thicknesses (cf. loc. cit (1965), FIGS. 8 to 10). With metal sheet sandwich systems the band width is advantageously defined as the range of the temperature interval within which the value $d_{\text{comb}}=0.05$ is exceeded. The damping of metal sheets which are not damped by additional vibration damping means in metal sheet constructions of various types corresponds to values $d_{\text{comb}} \leq 0.01$. The reference value d_{comb} of 0.05 thus means a considerable increase in the damping effect (by about 15 db (decibel)) as compared to the "nil damping" $d_{\text{comb}}=0.01$.

In the curve shown in FIG. 1c the reference value d_{comb} of 0.05 is exceeded in the mainly interesting frequency range of from 100 to 1,000 c.p.s. (Hz.) at temperatures ranging from about 0 to 50° C. The temperature band width thus corresponds to about 50° C. Sandwich systems of this type are suitable for many technical fields of application. By modifying the content of plasticizer, it is possible to shift the temperature band of a high damping effect to higher temperatures and thus to adapt the material to special technical uses, for example in machine units operating at elevated temperatures. This example of a metal sheet sandwich system comprising a self-adherent interlayer having optimum properties of a vibration damping material with a broad temperature band prepared by copolymerizing appropriate monomeric compounds has hitherto not been surpassed by other arrangements of similar kind and may be taken as standard for judging the acoustic efficiency of the system according to the invention.

FIGS. 1a to 1c show the temperature curves of the loss factor d_{comb} of metal sheet sandwich systems comprising steel sheets of a thickness of 0.5 millimeter each and damping interlayers of a thickness of about 0.7 and 0.3 millimeter (in FIG. 1c) for a frequency of 100 c.p.s. and 1,000 c.p.s.

The curves were measured with sandwich systems the interlayers of which consisted of

- (1a) A graft polymer of 50% by weight of methylmethacrylate on 50% of a copolymer of 35% by weight of vinyl acetate, 35% by weight of 2-ethylhexyl-acrylate, 20% by weight of dibutyl maleate and 10% by weight of crotonic acid (according to the invention),
- (1b) A graft polymer of 50% by weight of a mixture of 90% by weight of methylmethacrylate and 10% by weight of acrylic acid on 50% by weight of a copolymer of 35% by weight of vinyl acetate, 35% by weight of 2-ethylhexyl acrylate, 20% by weight of dibutyl maleate and 10% by weight of crotonic acid (according to the invention)
- (1c) A copolymer of 63% by weight of vinyl acetate and 37% of dibutyl maleate containing as plasticizer 15% by weight of 2-ethylhexyl phthalate and 15% by weight of tricresyl phosphate, calculated on the mixture.

The arrangements of the invention 1a and 1b whose monomer proportions lie in the optimum range have a very broad temperature band width with relatively high maximum damping values that come near to the values of arrangement 1b. With the arrangement 1a the center of damping is at 35 to about 50° C. with maximum damping values of about 0.4 to 0.9. The temperature band width is about 150° C. for 100 c.p.s. and about 115° C. for 1,000 c.p.s. The excellent vibration damping properties are maintained at a temperature of about -10° C. to about 120° C. With arrangement 1b the maximum value of d_{comb} is 0.4 to about 0.8 with a center of damping in a temperature range of from about 35 to about 45° C., the temperature band width being about 160° C. for 100 c.p.s. and about 110° C. for 1000 c.p.s. As in arrangement 1a the slow decrease of the damping towards high

and low temperatures, above all at low frequencies around 100 c.p.s. is especially favorable. The reference value d_{comb} of 0.05 is exceeded at a temperature in the range of from about -20 to about 120° C. As compared with the standard system 1c, arrangements 1a and 1b have an appreciably broader temperature band width and better vibration damping properties at about 0° C. and around 30° C. so that arrangements of this type are suitable for quite a number of applications not only at 0° C. but also especially at normal and elevated temperatures (for example in machines and appliances operated at normal and elevated temperatures). Owing to their content of 10% by weight of crotonic acid the graft polymers used in arrangements 1a and 1b can be cross-linked by reaction with a bifunctional or trifunctional compound (for example a compound containing a plurality of epoxide, isocyanate or similar groups), whereby the softening range and therewith the range of high damping can be shifted towards higher temperatures for special applications.

20 A special advantage of the vibration damping material of the present invention resides in the fact that it may be applied continuously during the mass production of the metal sheet sandwich systems.

For this purpose the vibration damping material can be used (1) in the form of the finished graft polymer and (2) in the form of a solution of the specified copolymer in the methyl methacrylate or methylmethacrylate/acrylic and/or methacrylic acid mixture to be grafted on the copolymer and containing the polymerization catalyst, and the graft polymer can be produced by a thermal treatment at a temperature in the range of from about 60 to about 180° C. for the sandwich system comprising the said solution as interlayer. It is a thermoplastic adhesive which may be applied to the metal sheets by trowelling, brushing or pouring at elevated temperature. The sandwich system may then be advantageously cooled under pressure between rollers. Except for degreasing the metal sheets do not require a preliminary treatment and further adhesive. Owing to the content of the copolymer of crotonic acid degreasing may even be dispensed with. The adhesion is very good.

45 The vibration damping material of the present invention has a good resistance to flow. The metal sheet sandwich system may, within broad limits, be processed as normal metal sheets, that is they may be creased, bent, shaped, welded and riveted. In this manner laminated systems are obtained having a damping height and temperature range of damping which makes them well suitable for many applications at normal and elevated temperatures.

50 Minor amounts of fillers, for examples for improving the electric conductivity (improvement of resistance welding) may be incorporated in the vibration damping materials. In order not to affect the damping effect adversely it is advantageous to use less than 1% by weight, preferably less than 0.5% by weight of filler, calculated on the polymer. Suitable fillers are, for example, heavy spar, silicic acid, graphite and soot.

The metal sheet sandwich system suitably has a total thickness in the range of from 1 to 6 millimeters. The interlayers may have a thickness of 0.1 to 1 millimeter, preferably 0.2 to 0.5 millimeter. A maximum damping effect is obtained with symmetrical laminated systems. With an equal weight, asymmetrical laminated systems have, however, a higher stiffness in flexure and strength. Asymmetrical laminated systems are, therefore, preferred for those applications which require a high strength with respect to the weight. The ratio of the thicknesses of the outer plates or metal sheets is preferably within the range of from 1:1 to 1:4.

FIG. 2 of the accompanying drawings shows sandwich systems with symmetrical arrangement (a) and asymmetrical arrangement (b) in which the interlayer 2 is interposed between the two outer plates or metal sheets 1.

What is claimed is:

1. A vibration damped sandwich system comprising two hard plates and interposed between the plates a vibration damping interlayer comprising graft polymers of 40 to 80% by weight of methylmethacrylate or methylmethacrylate together with 0.1 to 10% by weight of acrylic acid, methacrylic acid, or mixtures thereof, on 60 to 20% by weight of a copolymer of 30 to 40% by weight of vinyl acetate, 30-40% by weight of 2-ethylhexyl acrylate, 30 to 10% by weight of dibutyl maleate and 5 to 15% by weight of crotonic acid.
2. A vibration damped sandwich system as claimed in claim 1, wherein the hard plates are metal sheets.
3. A vibration damped sandwich system as claimed in claim 1, wherein the polymer of the interlayer contains up to 1% by weight of a filler, calculated on the polymer.
4. A vibration damped sandwich system as claimed in claim 1, wherein the ratio of the thicknesses of the plates lies in the range of from 1:1 to 1:4.
